UNITED STATES PATENT OFFICE.

ROBERT PITCHER WOODWARD, OF BROOKLYN, NEW YORK.

SHIRT AND CHEST PROTECTOR.

SPECIFICATION forming part of Letters Patent No. 476,503, dated June 7, 1892.

Application filed August 5, 1891. Serial No. 401,738. (No model.)

To all whom it may concern.

Be it known that I, ROBERT PITCHER WOODWARD, a citizen of the United States, residing at Brooklyn, in the county of Kings and State 5 of New York, have invented certain new and useful Improvements in Shirt and Chest Protectors; and I do hereby declare the following to be a full, clear, and exact description of the invention, such as will enable others skilled 10 in the art to which it appertains to make and use the same.

My invention relates to improvements in chest and shirt protectors adapted to be worn under the shirt at the front or back of the 15 person in the usual manner, so as to protect the chest and lungs from cold; and the object of the invention is to provide an article of this character which is adapted to serve both as a protector for the chest and lungs 20 and as a protector or shield for the bosom of the shirt or chemisette, so as to prevent the latter from being soiled and wrinkled by absorbing the perspiration of the body.

Chest-protectors of the usual construction 25 are subject to objection in use on account of the fact that they soon become dampened or wet by the perspiration of the body, and are thus rendered uncomfortable to the wearer, and being in contact with the shirt or chemisette 30 sette the latter absorbs the moisture and soon becomes soiled and wrinkled, particularly in warm weather or under conditions which produce free perspiration.

The object of my invention is to overcome 35 these objections and at the same time to provide a cheap, light, effective, and durable chest-protector, which shall also serve to keep the shirt and underclothing dry, and thus prevent the latter from sticking to the skin, as is 40 usual in warm weather or at other times when the wearer of such protectors perspires freely.

In the accompanying drawings I have illustrated one form of protector embodying my invention; but it will be understood, of course, 45 that the size and shape of the article and the material used in manufacturing the same may be varied at pleasure to adapt the same to different uses and to suit the taste of different individuals without departing from the spirit 50 of my invention, which consists, essentially, of a shirt and chest protector comprising a piece or sheet of flexible material with strips

of light and yielding material secured to the inner face of the sheet, so as to form air-circulating spaces or channels between the 55 strips, whereby a free circulation of air is permitted in and about the article, between the body of the wearer and the shirt or underclothing in contact with the protector, so as to adapt the article to serve the double purpose 60 of protecting the lungs and keeping the shirt-bosom or underclothing dry.

The invention consists, further, in certain improved features of construction, all as will be hereinafter described, and particularly 65 pointed out in the claims at the end of this description.

Referring to the drawings, in which like letters of reference are used to designate like parts of the article, Figure 1 represents a 70 front view of the shield or protector having portions of the outer piece or ply of the article torn off, so as to show the interior construction; and Fig. 2 is a sectional view taken on a line which passes longitudinally through 75 the article from top to bottom thereof.

A designates the shield or protector, which may consist of one or more pieces or plies a 80 of cloth, paper, gauze, or any other suitable thin, light, and flexible material, to which may be attached strips or pieces B of felt, cork, paper, or any suitable light and flexible or elastic material, so as to provide air spaces or channels A' between said strips for the purpose of permitting the air to circulate 85 in and about the protector between the shirt and the undergarment or body of the wearer.

The protector preferably consists of a piece of cloth or fabric having suitable strips of 90 felt or cork secured to the inner side thereof, these strips preferably running transversely of the article and being arranged at suitable distances apart to provide channels or spaces A' between them, extending from side to side 95 of the protector, and when two or more pieces or plies of material are used, as shown, the edges of the fabric are not stitched or sewed together, but are left free, so as to be held apart and supported in this position by the 100 yielding strips, whereby the ends of the channels or air-spaces are kept open to permit the air to enter and circulate freely through the same. To facilitate the circulation of the air

in and about the article the cloth or fabric may be perforated, as indicated at C, and when two or more plies are used either or both plies may be perforated. This construction permits a free circulation of the air in and about the article, and as the confined air is tempered by the heat of the body it will tend to keep the underclothing dry, and at the same time will impart a comfortable and cooling effect to the wearer in a warm atmosphere. The strips or bits of felt, cork, or other similar soft and yielding material also give sufficient rigidity to the article and prevent the shirt-bosom or chemisette from coming in contact with the moisture of the body or undergarment, thereby preventing the latter from becoming wrinkled and soiled.

The device thus serves the double purpose of shielding the shirt from moisture and protecting the chest and lungs in a healthful, effective, and comfortable manner.

In using the article it may be worn suspended about the neck by a band, as at D, or it may be secured and supported in position in any suitable and well-known manner. An elastic or other suitable strap f, with clasp F, may be attached to the lower extremity of the article and secured to the undergarment, or the article may be suspended at the front or back of the body and secured in place by a belt or girdle passing around the waist. If desired, a duplex protector may be provided, so as to protect both the chest and back of the body, by making a pair of protectors which may be connected and suspended by straps resting upon the shoulders, and any suitable means may be employed for adjusting and securing the protectors in position at the front or back.

It will be understood, of course, that I do not limit myself to the use of any particular kind of material for making the article, so that it is sufficiently light and flexible for the

purpose, nor to one or two plies or pieces for the main body of the protector, and the term 45 "light and flexible" material, as herein employed, comprehends any suitable material for the purpose, though I preferably use felt or cork for the strips. It will also be readily understood that the strips B may consist of 50 short pieces or bits of any suitable light and flexible material arranged transversely or longitudinally or in any desired manner adapted to provide the open-ended channels or spaces for the circulation of the air.

Having thus described my invention, what I claim, and desire to secure by Letters Patent, is—

1. A shirt and chest protector comprising a sheet of flexible material, with strips of light 60 and yielding material secured to the inner face of the sheet, so as to form air-circulating spaces or channels between the strips, substantially as described.

2. A shirt and chest protector comprising a 65 sheet of flexible material, with strips of light and yielding material secured to the inner face of the sheet and extending transversely thereof at intervals, so as to form intervening air-circulating spaces or channels, substantially 70 as described.

3. A shirt and chest protector comprising two or more plies of flexible material, with strips of light and yielding material secured thereto at intervals between the plies, so as 75 to form air-circulating spaces or channels, the edges of the plies being free between the strips, so as to leave the ends of the air-circulating spaces or channels open, substantially as described.

In testimony whereof I affix my signature in presence of two witnesses.

ROBERT PITCHER WOODWARD.
